UNITED STATES PATENT OFFICE

FRITZ ALLENDORFF, OF STUTTGART, GERMANY, ASSIGNOR TO ROBERT BOSCH AKTIEN-
GESELLSCHAFT, OF STUTTGART, GERMANY

MAGNETO IGNITION APPARATUS

Application filed February 12, 1932, Serial No. 592,645, and in Germany February 23, 1931.

The present invention relates to a magneto ignition apparatus in which the interrupter with the rotary magnet and the stationary armature are arranged combined in a closed 5 chamber. The distributor and the distributor gearing are usually placed in a second closed chamber.

In order to obtain, for such magnetos, a suitable ventilation of the interrupter and of 10 the distributor even in dusty situations, both chambers according to the invention, are provided with ventilation openings which are protected by known means against the penetration of dust and water.

15 An example of construction of the invention is shown in the accompanying drawings, in which:—

Figure 1 shows a magneto ignition apparatus, partly in section.

20 Figure 2 a view of the bottom of the casing, Figure 3 a section of Figure 1, on the line A—A.

Figure 4 an elevation of a protective cap.

In Figure 1 the front wall of the magneto 25 casing *a* together with the bearing cover *b* and the cover *c* of the magneto encloses a chamber in which are arranged the rotary magnet *d*, the armature body *e* with the coil *f* and the interrupter *g*. On the other side of 30 the wall *a* is located the rotary distributor piece *h* with the distributor gearing *i*. A closed chamber is here formed also by the front wall *a* of the casing, a part *m* of the bottom of the casing, a metal cover *n* and the 35 distributor disc *o*. In each of the longitudinal walls *p* (Figure 3) of the magneto casing is an opening *q*, which is closed by a piece of felt *s* laid between two perforated plates *r*. These openings are covered by caps *t*, the edge 40 *u* (Figure 4) of which has a cut away part *v* only on the lower side, so that water running on to the magneto or sprayed against it cannot penetrate into the opening *q* in the casing.

In the bottom of the casing *a* is an opening 45 *w*. The path of the air which, when the

magneto is erected, can generally enter only from the side, is so formed by means of ribs *x* in the bottom of the casing and openings *y* in the ribs, that the air must change direction several times during its course. The path of 50 the air is indicated by the arrows in Figure 2. A passage *z* leads from the opening *w* to the chamber in which the distributor is located.

By the ventilation arrangement described, 55 oil vapours arising in the chamber of the magneto and the gases formed by the sparking of the interrupter are removed and replaced by fresh air, without dust or water being able to penetrate into the interior of 60 the magneto.

I declare that what I claim is:

1. A magneto ignition apparatus comprising an armature, a magnet rotatable relatively to said armature, an interrupter, a 65 chamber having ventilating openings therein enclosing said armature, magnet and interrupter, a distributor, a chamber enclosing said distributor and means to protect said ventilating openings.

2. A magneto ignition apparatus comprising an armature, a magnet rotatable relatively to said armature, an interrupter, a chamber having ventilating openings therein enclosing said armature, magnet and interrupter, a distributor, a chamber having 70 ventilating openings enclosing said distributor, and means to protect said ventilating openings from the penetration of dust and water.

3. A magneto ignition apparatus comprising an armature, a magnet rotatable relatively to said armature, an interrupter, a chamber having two axially parallel walls provided with ventilating openings enclosing 85 said armature, magnet and interrupter, a distributor, a chamber enclosing said distributor, covers permeable to air but impermeable to dust in said ventilating openings and caps 90 cut away at the bottom shielding said covers.

4. A magneto ignition apparatus comprising an armature, a magnet rotatable relatively to said armature, an interrupter, a chamber having ventilating openings enclosing said armature, magnet and interrupter, a distributor, a chamber enclosing said distributor, a rib on the base of said first mentioned chamber having openings therein to form a labyrinth path and an opening between said ribs communicating with said chamber enclosing the distributor.

5 10
In testimony whereof I have hereunto
affixed my signature.

FRITZ ALLENDORFF.
